UNITED STATES PATENT OFFICE

HANS HUBER, OF ZURICH, SWITZERLAND, ASSIGNOR TO FIRM P. F. A. G. PATENTVERWERTUNGS- & FINANZIERUNGS-AKTIENGESELLSCHAFT, OF ZURICH, SWITZERLAND

FEED DEVICE

Application filed August 2, 1930, Serial No. 472,708, and in Switzerland August 31, 1929.

This invention relates to improvements in feed devices in machines for quantity production of articles from bar-shaped stock material, such as wooden spools. The number of revolutions of machines of this kind, necessarily requiring to be very high, considerable friction arises between the bar to be worked which is inserted with clearance in the hollow vertical machine spindle and the inner circumference thereof due to the action of residual centrifugal force moving the bar in close contact with this circumference. Thus automatic feed motion of the bar by gravitation at this high speed being impeded it is necessary to provide a feed device for counteracting this frictional resistance and advancing the work blank in the downward direction. The next succeeding work blank to the one being worked dropping down from the supply means of the feed device without circumferential movement is turned about its axis, at the moment it hits with its front face the end face of the lower bar, by frictional engagement between these two faces which is proportionate to the weight of the upper bar, so that the latter has not imparted to it the full rotational speed of the lower power driven bar of between 4500 and 6000 revolutions per minute. The upper bar thus rotating at a speed of only say 1000 revolutions is capable of following the lower bar in its downward movement, with the abutting end faces remaining in frictional engagement, by gravitation alone, its residual centrifugal force not being sufficient to counteract this movement due to frictional engagement between it and the wall of the bore of the hollow working spindle when this bar is moved one-sidedly through the clearance space between it and said bore and before this bar is chucked and its circumferential speed increased to the high value after the lower bar has been used up.

The object of the present invention is to provide suitable feed means for this purpose and according to the invention in the feed device a clamping appliance for moving the bar in the one direction of movement a reciprocating saddle is provided on said clamping appliance being actuated by the displace-

ment of a carriage relatively to the saddle, the said carriage being axially shiftably mounted with respect to the latter.

In the accompanying drawings an embodiment of the invention is illustrated by way of example only, wherein

Fig. 1 is an axial section of a feed device;

Figs. 1a and 1b, are similar views to Fig. 1

with certain parts in different positions;

Fig. 2 a side elevation of Fig. 1;

Fig. 3 is a top plan view of the device, on a smaller scale;

Fig. 4 is a section on the line IV—IV in Fig. 1, showing the escapement mechanism;

Fig. 5 is a fragmentary section on the line V—V in Fig. 1 showing the locking means for the saddle;

Fig. 6 shows a top plan view of the saddle, with a section through one of the engagement rollers of the clamping device;

Fig. 7 is a section on the line VII—VII in Fig. 1;

Fig. 8 is a front elevation of a machine for quantity production of wooden spools with the feed device according to the invention applied thereto, and

Fig. 9 is a side elevation to Fig. 8.

In the frame 1, a hollow saddle 2 is vertically reciprocatorily arranged on which a carriage 17 is mounted to be axially shiftable relatively thereto. The carriage carries a roller 3 which cooperates with a curved guideway 4 on a cam body 5 secured to the control shaft 6. When the shaft 6 is turned the carriage and thereby the saddle 2 is moved upwardly by means of the cam body against the action of springs 7 which are arranged on guide bars 8 for the saddle 2 between the latter and the upper wall of the frame 1. The springs 7 tend to move the saddle 2 and the carriage 17 in contact with the guide-way 4 on the body 5. The carriage 17, and indirectly the saddle 2 with it, in their lower end position rest against a rubber buffer 10 which is removably connected to the carriage 17 opposite an abutment member 12 mounted on springs 11 which are carried on supports 9 adjustably arranged on the bars 8. The buffer 10 and the springs 11 counteract the blow exerted

on the carriage 17 when the carriage 17 is moved upwardly by the cam body 5.

When the carriage 17 is moved upwardly by the cam body 5, the carriage 17 moves the saddle 2 upwardly, the carriage 17 being axially shiftably mounted on the saddle 2.

When the carriage 17 is moved upwardly by the cam body 5, the carriage 17 moves the saddle 2 upwardly, the carriage 17 being axially shiftably mounted on the saddle 2.

When the carriage 17 is moved upwardly by the cam body 5, the carriage 17 moves the saddle 2 upwardly, the carriage 17 being axially shiftably mounted on the saddle 2.

When the carriage 17 is moved upwardly by the cam body 5, the carriage 17 moves the saddle 2 upwardly, the carriage 17 being axially shiftably mounted on the saddle 2.

When the carriage 17 is moved upwardly by the cam body 5, the carriage 17 moves the saddle 2 upwardly, the carriage 17 being axially shiftably mounted on the saddle 2.

When the carriage 17 is moved upwardly by the cam body 5, the carriage 17 moves the saddle 2 upwardly, the carriage 17 being axially shiftably mounted on the saddle 2.

on them by the saddle 2, forced downwardly by the action of the springs 7 by cushioning it.

Between the saddle 2 and the carriage 17 a compression spring 18 is inserted which tends to press these parts apart.

The saddle is provided with a bore 2b through which the bar 20 to be worked is passed and at the same time guided thereby.

- 10 In order to secure and center the bar 20 in the saddle 2 three slides 21 are provided which enter in radial guides of the saddle to be easily displaceable therein and each of which is provided with a roller 22 for engaging the bar 20 and mounted on a ball bearing. For moving the slides 21 radially, a two-armed lever 24 is linked for each slide (Fig. 7) to a flange of the saddle 2. The one arm of this lever projects in a recess of the slide 21 and the second arm thereof engages in a slot 26 in a rib of the carriage 17. The slot 26 is inclined with respect to the axis of the carriage 17 so that when the latter is axially shifted relatively to the saddle 2 the slide 21 is radially displaced and thereby the guide roller associated therewith is brought to bear on the work blank 20 or moved away from it respectively. Besides, on the saddle 2 a hook 28 is secured.

- 20 When the carriage 17 and thereby the saddle 2 is moved upwardly by means of the guideway 4 against the action of springs 7 (Fig. 1) the hook 28 grips behind a radially displaceable bolt 29 which is displaceably mounted in the upper part of the frame 1. For the displacement of this bolt a cam disk 30 carrying a stud 31 (Fig. 5) is provided on the control shaft 6. The said stud on the rotation of the shaft 6 engages with the one arm of a two-armed lever 33 which is mounted on a pivot 32 of the frame 1 and the other arm of which cooperates with the bolt 29 to pull the latter radially inwardly so as to release the hook 28 when the stud 31 hits the lever 33. Immediately after the saddle 2 is secured by the bolt 29 the carriage 17, by action of the spring 18 which now expands thus holding the carriage pressed against the cam body 5, during the downward movement of the same, causes the rollers 22 on the saddle 2 to firmly clamp the bar 20 by rolling frictional engagement arising between the bar and the rollers, when they begin to run on their ball bearings (Fig. 6). By the arrangement of these ball bearings that loss of rotational speed of the bar is due to the engagement between the bar and the rollers is reduced to a minimum.

- 30 As soon as the rollers 22 have gripped the bar 20 the bolt 29 releases the hook 28, whereafter the saddle 2 together with the bar 20 and the carriage 17 are pushed downwardly by means of the springs 7. Thus the saddle 2 and the carriage 17 are released by rotation of the control shaft. The moment

the carriage 17 hits the abutment member 12 by the removable buffer 10 the spring 18 is compressed by the weight of the saddle 2 and the thrust caused by the released springs 7 whereby the clamping appliance is opened. Thus the saddle 2 hits indirectly on the buffer 10 by the intermediary of the carriage 17, so that its kinetic energy is actually destroyed by the elasticity of the buffer springs 11.

75 To enable further bars 20 to be fed by the device a drum-shaped supply rack is provided having guide tubes 36 spaced at equal distances from the centre (Fig. 3) and each adapted to accommodate a bar 20. The supply rack 35 is disposed coaxially with the control shaft 6. The radial distance of the guide tubes 36 is such as to allow one of the said tubes at a time to be adjusted coaxially with the bore 2b. The feed motion of the guide tubes 36 is automatically effected by the aid of an escapement mechanism including a ratchet wheel 39 connected to the supply rack 35. A pawl 40 linked to a feed lever 41 cooperates with the teeth of the ratchet wheel 39 (Fig. 4). The lever 41 which is mounted on the shaft 6 to freely rock thereabout and is acted upon by a spring 42 is displaceable by means of the cam disk 30 and a two armed lever 45 against the action of the spring 42. The lever 45 is linked to the frame 1 and a roller turnably mounted on the one arm of this lever cooperates with the cam disk 30, whilst a stud on its other arm engages in a slot of the lever 41. Thus during one full revolution of the shaft 6 the supply rack 35 is advanced one feed step, whereby a guide tube 36 is moved in alignment with the saddle 2 to allow a fresh bar to drop down into the bore 2b of the latter.

105 The lever 41 projects radially so far out that it is enabled to pass beyond the upper guide member 46 which is formed by an incision in the top of the frame 1 and centrally disposed above the bore 2b of the saddle 2 for guiding the work blanks 20 in alignment with said bore. In this manner the lever 41 is adapted to bear against the bar 20 which is passing into the bore 2b through the guide tube 36 which has been turned to register with the guide member 46, whereby the pawl 40 is rendered inoperative its angular displacement being reduced thus preventing the pawl from gripping behind the next tooth on the ratchet wheel.

110 Consequently, the rack 35 is at standstill and arrested in this position by a spring pressed stop tooth 44, until, after the upper end of the bar 20 having passed the lever 41, the latter swings back by action of the tensioned spring 42, whereupon the rack is advanced a step by the pawl 40 engaging behind the next tooth on the ratchet wheel 39, and the lever 45 being correspondingly moved by means of cam disk 30 so that a fresh

work blank is caused to drop into the bore 2b.

The feed mechanism is adapted to be angularly shifted about the control shaft 6.

The Figs. 8 and 9 show how the feed device according to the invention may be applied to a machine 50 for quantity production of wooden spools, having a motor driven hollow spindle 51 through which the work blanks 20 are fed step by step to a lower working chamber 52. Behind this chamber in a separate compartment 53 where the motor driven gearing 54 for the control shaft 6 is housed, the feed device being mounted directly above on the casing of the machine. Suitably the stop sleeves 12 and the cam body 5 are adjustably arranged, so as to enable the vertical feed step for the work blanks to be varied.

I claim:

1. In a feed device for machines for quantity production of articles from bar-shaped stock material, in combination, a reciprocatory saddle, a clamping appliance provided on the said saddle for feeding the bar in the one direction of movement of the saddle, a locking member radially displaceable relatively to the said saddle for securing the latter in the one of its end positions, means for releasing the said locking member, a carriage axially displaceably mounted on the said saddle for actuating the said clamping appliance, means for moving the said carriage and the said saddle apart for closing the said clamping appliance, and means for conveying the saddle together with the carriage and the clamped bar into the other end position for advancing the bar one longitudinal feed step.

2. In a feed device for machines for quantity production of articles from bar-shaped stock material, in combination, a vertically reciprocatory saddle, a clamping appliance provided on the said saddle for feeding the bar in the one direction of movement of the saddle, a spring loaded carriage axially displaceably mounted on the said saddle for actuating the said clamping appliance, a flange on the said carriage for the saddle to rest on, a cam body, means on the said carriage cooperating with the said cam body, for lifting the said carriage and the said saddle bearing on its flange against spring action, and for lowering the said carriage assisted by elastic spring force, and means for actuating the said clamping appliance when the said carriage is shifting on the said saddle.

3. In a feed device for machines for quantity production of articles from bar-shaped stock material, in combination, a reciprocatory saddle, radially adjustable slides on the said saddle, a roller in each slide for clampingly engaging with the bar, a carriage, a bore in the said carriage embracing the said saddle to adapt the said carriage to be axially

displaceable on the said saddle, a slot on the said carriage for each slide obliquely disposed to the axis of the said bore, and a two-armed lever between each of the said carriages engaging with its one end in the said slot and with its other end in the said slide so as to shift the rollers on the latter radially when the carriage is axially displaced relatively to the said saddle.

4. In a feed device for machines for quantity production of articles from bar-shaped stock material, in combination, a reciprocatory saddle, a clamping appliance provided on the said saddle for feeding the bar in the one direction of movement of the saddle, a locking member radially displaceable relatively to the said saddle for securing the latter in the one of its end positions, a carriage axially displaceably mounted on the said saddle actuating means between the said clamping appliance and the said saddle, a control shaft for driving the said saddle, the said carriage, and the said locking member, and means for actuating the said clamping appliance when the said carriage is shifting on the said saddle.

5. In a feed device for machines for quantity production of articles from bar-shaped stock material, in combination, a vertically reciprocatory saddle, a clamping appliance provided on the said saddle for feeding the bar in the one direction of movement of the saddle, a carriage axially displaceable relatively to the said saddle, resilient stop means on the machine frame for damping the blow exerted on the latter by the downwardly moving carriage, and means for opening the said clamping appliance when the said carriage is hitting the said stop means.

6. In a feed device for machines for quantity production of articles from bar-shaped stock material, in combination, a reciprocatory saddle, a bore in the said saddle, a clamping appliance provided on the said saddle for feeding the bar in the one direction of movement of the saddle, a carriage axially displaceable relatively to the said saddle, a drum-shaped supply rack for the stock material, an escapement mechanism, means for rendering the said mechanism inoperative as long as sufficient stock material is present in the said bore, and means for actuating the said clamping appliance when the said carriage is shifting on the said saddle.

7. In a feed device for machines for quantity production of articles from bar-shaped stock material, in combination, a reciprocatory saddle, a bore in the said saddle, a clamping appliance provided on the said saddle for feeding the bar in the one direction of movement of the saddle, a carriage axially displaceable relatively to the said saddle, a drum-shaped supply rack for the stock material, an escapement mechanism, a pawl, a feed lever in the said escapement

mechanism carrying the said pawl and projecting in the path of the stock material passing through the said bore so that each bar coinciding with the said lever renders the lever and thereby the pawl inoperative, and means for actuating the said clamping appliance when the said carriage is shifting on the said saddle.

8. In a feed device for machines for quantity production of articles from bar-shaped stock material, in combination, a reciprocating saddle, radially movable slides on said saddle, a roller mounted on each slide and adapted to rotate on said saddle in unison with the stock when engaging the same by rolling frictional contact, a carriage axially displaceable relatively to said saddle, and means provided between said carriage and said slides for moving the latter to grip the stock between said rollers under maintenance of the rotational speed imparted to the stock by the machine.

In testimony whereof I have signed my name to this specification.

25 HANS HUBER.
